WILLIAM GAVILLET AND LOUIS MARTARESCHE, OF PARIS, FRANCE.

GAS-MOTOR.

SPECIFICATION forming part of Letters Patent No. 357,193, dated February 8, 1887.

Application filed June 4, 1886. Serial No. 204,145. (No model.) Patented in France November 16, 1885, No. 172,302; in Belgium March 13, 1886, No. 72,348; in Luxemburg March 17, 1886, No. 664; in Austria-Hungary March 22, 1886, No. 12,181 and No. 38,927; in Spain March 24, 1886, No. 9,205; in England March 27, 1886, No. 4,321, and in Italy April 5, 1886, No. 19,749.

To all whom it may concern:

Be it known that we, WILLIAM GAVILLET and LOUIS MARTARESCHE, citizens of the Republic of France, residing at Paris, France, have invented certain new and useful Improvements in Gas-Motors, (for which we have obtained Letters Patent in France, bearing date November 16, 1885, No. 172,302; in Belgium March 13, 1886, No. 72,348; in Austria-Hungary March 22, 1886, No. 12,181 and No. 38,927; in England March 27, 1886, No. 4,321; in Luxemburg March 17, 1886, No. 664; in Italy April 5, 1886, No. 19,749; in Spain March 24, 1886, No. 9,205;) and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Referring to the accompanying drawings, Figure 1 is a side elevation; Fig. 2 a top plan view, and Fig. 3 a vertical longitudinal central section, of our improved gas-engine. Fig. 4 is a transverse section of the same on the line $x-x$ of Fig. 2. Fig. 5 is a longitudinal vertical section of the valve-casing, taken on line $y-y$ of Fig. 2. Figs. 6 and 7 are end views of the engine. Fig. 8 is a detail sectional view of the bobbin of the electro-magnet; and Fig. 9 is a sectional end view of the engine, showing the electric devices for igniting the charge.

The invention has for its object to increase the efficiency and operation of gas-engines and to simplify their construction; and it consists, essentially, in constructing the cylinder of a single piece contracted at one end and inclosed or surrounded by a cooling-jacket.

The invention further consists in a novel arrangement and construction of mechanism and combination of mechanisms for introducing the charges into the cylinder, for regulating and igniting said charges, and for exhausting the spent gases from the cylinder.

The invention consists, lastly, in a novel construction of a generator of electricity for igniting the charges.

In our improved gas-engine that portion of

the cylinder C which constitutes the piston-chamber C' is surrounded by a cooling-jacket, c, while that portion of said cylinder which constitutes the combustion-chamber C² is or may be devoid of such cooling-jacket, according to the gaseous compound employed as a motive power. When certain gaseous compounds are used, more especially compounds derived from liquid fuel—such as hydrocarbon oils and other like gaseous compounds—much better results are obtained when such gases are brought into contact with highly-heated surfaces, the heat of which not only completely gasifies the non-gasified portions thereof, but also tends to expand the gaseous compound, (vapor and air or air and other gas,) which, as is well known, results in a greater amount of power developed and a corresponding economy in gaseous fuel. In this manner the usual superheating devices for superheating the gaseous compound before admission into the combustion-chamber may be dispensed with. When, however, a gaseous compound is employed which requires no superheating, or when such superheating may become detrimental to the efficient working of the engine, the combustion-chamber C² may be surrounded by a cooling-jacket, c², as shown in Fig. 3.

If desired, instead of utilizing the jacket c² for purposes of cooling the combustion-chamber, the said jacket may be filled with a non-conductor of heat, to prevent loss of heat by radiation, and thus more effectually superheat the charges; or the portion of the cylinder in which is formed or which constitutes the combustion-chamber may be enveloped in a non-conductor of heat—such as asbestos or other like material—and, finally, if a jacketed combustion-chamber is employed the spent gases from the cylinder may be exhausted through said jacket to heat that portion of the cylinder and prevent radiation, the said spent gases escaping from the jacket at v^x, and being admitted thereto through exhaust-passage e and exhaust-valve V' and valve-chamber v', as shown in Fig. 9. This cylinder C we construct of one piece, thereby effecting a greater economy in the construction of the engine.

The cylinder C is open at one end and closed at the other by a head, C². The piston is of any appropriate construction, and is pivoted to its piston-rod R, which latter is in turn connected, as usual, with the crank-shaft S. The shaft S carries a helicoidal pinion, P, that meshes with a corresponding wheel, W, on a counter-shaft, S', arranged at right angles to shaft S along one side of the engine, and said shaft S carries, as usual, a fly-wheel, W'.

Upon shaft S' is secured a pulley, p', that is connected by belt with the driving-pulley of a pump, A, Figs. 1 and 2, and which pumps the water from the base B of the engine-frame 15 (which base is hollow and serves as a water-reservoir) into the jacket c' of the cylinder.

Any well-known means for lubricating the power-cylinder may be employed. We prefer, however, to employ a lubricator that is 20 controlled by the movements of the piston, and in such a manner that the quantity of the lubricating agent fed to the power-cylinder and distributed over the inner surface thereof by said piston will be regulated by the speed 25 of the latter, and the feed automatically cease with the movements of said piston. Such an arrangement of devices we will now describe.

The power-cylinder is automatically lubricated by means of the following devices: O, 30 Figs. 1, 2, and 3, is an oil-cup, in which is arranged a feed-tube, t, whose upper end is beveled off, as at t', and whose lower end communicates with the interior of the piston-chamber C' of the cylinder C.

Upon a shaft, s, that has its bearings in the oil-cup, is mounted a pulley, p, and a sprocket or toothed wheel, w, over which travels an endless chain, a, to which is attached an oil-carrier, a', which may consist of a brush, a sponge, or a carrier of other like material, that dips into the oil, and as it travels over the upper end of the feed-tube t engages the cut-away or beveled portion t', and the oil held thereby is thus squeezed out and runs down the feed-tube t into the cylinder, to be taken up by the piston. To keep the chain at a proper tension, we provide a tension-pulley, p², which is preferably made adjustable vertically in any usual well-known or desired 50 manner.

The chain a is operated from the governor G by means of the pulley p, belted to a pulley, p², on a shaft, s², that carries a bevel-pinion, b², which meshes with a like pinion, b', on the 55 governor-shaft s'. The latter is driven from shaft s², and said shaft s² from the crank-shaft S, through pulleys p³ p⁴, on shafts s² S, and a crossed belt, b².

Of course when the engine is not in operation the oiling devices cease also to operate, as will be readily understood.

The admission of the gaseous compound is effected as follows: Upon the counter-shaft S' is secured a sleeve, D, that has a cam or groove, d', in which rides a lug, or, preferably, a friction-roller, l', on the end of the arm L' of a lever, L, pivoted to the side of the engine, where-

by said lever receives a uniform oscillating movement on its fulcrum or pivot-pin l', the arm L' of lever L has a recess, l', that faces the 70 stem v of the admission-valve V, the other end, l², of the lever-arm L' has a longitudinal perforation that communicates with the recess l', and contains a pin or lug, l³, that terminates in a loop or oblong eye, l⁴. To the lower end 75 of the spindle of the governor G is connected a horizontal pin, g, Fig. 1, that lies within the eye l⁴ of the pin l', the said pin being of such length as to nominally project into the recess l' in the lever L' in the path of the valve-stem 80 v. The regulating-valve V is held to its seat in the valve-casing by a spring, e, Fig. 5, and the gaseous compound is admitted to the valve-casing by port or pipe E.

It is obvious that as long as the crank-shaft 85 S rotates at a given or normal speed the valve V will be actuated by the pin or lug l' at each oscillation of the lever L to admit a charge to the distributing valve-case or valve V²; but when the speed of the crank-shaft increases 90 the pin g will be drawn vertically out of the recess l', and consequently out of the path of the valve-stem, and said valve will not be actuated to admit a charge to the cylinder, as will be readily understood. 95

The gaseous compound passes from the valve-casing F of valve V into valve-casing F², in which are arranged the exhaust-valve V' and the distributing-valve V², and these valves communicate by passages or ports with 100 the combustion-chamber C² of the cylinder C. These two valves V' and V² are timed by and operated from the crank-shaft S; through the counter-shaft S' and the cams I and H, said valves being held to their seats by gravity and 105 by the power of coiled springs e' e², respectively, as shown in Fig. 1. In order to cause said valves to move in vertical planes the cams H and I, instead of acting directly upon the valve-stems, are caused to impinge upon plate 110 or leaf springs h and i, respectively, as shown in Figs. 1 and 4.

The ignition of the charges in the combustion-chamber C² may be effected in the following manner, referring more particularly to 115 Fig. 6: Upon shaft S' is mounted a cam, K, which is insulated from the shaft, and upon said cam bears a contact-spring, n, connected with a binding-post, N, and in electrical connection with the wire n'. The said binding-post N also carries a contact-screw, N', in electrical connection by wire n² with the igniter N². The current is derived from an induction-coil, (not shown,) and passes to the contact-spring n, and as the nose k of cam K lifts the spring 120 into contact with the screw N' the current passes to the igniter N², when a spark is produced in the usual manner, said current returning by wire n³ to the induction-coil. The ignition of the charge may be regulated by adjusting the screw N' in its support n⁴ on binding-post N, as will be readily understood. 125

Although the means described for igniting the charges are very simple and efficient and

readily adjusted, we prefer to employ the means shown in Figs. 3, 7, 8, and 9, inasmuch as the usual electric battery or other electric generator may be dispensed with, the igniting devices embodying in themselves the electric generator.

M M are a series of magnets provided with concave pole-pieces m m, said magnets being insulated from and supported by suitable brackets, m', secured to a frame, M', at the end of the cylinder C. Between the poles of the magnets is arranged an armature, Q, consisting of a soft-iron core, q, upon which are wound a number of insulated wires, q'. The armature Q is secured to disks or heads H at opposite ends, provided with trunnions h, arranged to rotate in bearings h', the said heads being insulated from the bearings; or, if desired, the heads may be insulated from the armature.

The magnets are of simple polarity in order to increase the magnetic force, while the armature is bipolar, its poles being concentric with their axes and connected together through their soft-iron cores, and when the engine is at rest the induced circuit through the armature is closed.

It is obvious that when the armature is suddenly rotated the circuit is not only interrupted to produce the electric spark at the igniter, but an induced reverse current is produced in the armature wire, that greatly increases the power of the electric spark at the igniter.

At one of the armatures is arranged a collector, R, which has as many metallic blocks as there are sections in the armature-wire, the ends of each wire of the sections being connected with one of the blocks of the collector, and said sections may vary in number according to the conditions of use, the number of metallic blocks of the collector varying correspondingly. The electric currents are taken from the collector by two brushes, R', isolated from each other, and secured to one of the trunnions of the heads H of the armature.

The armature is rotated as follows: The cam K, above referred to, instead of being provided with a nose or projection, k, has a shoulder, k', that engages with a hook at the end of a rod, r, pivoted to an arm, r', mounted on the trunnion of one of the heads of the armature, said rod r being held in contact with the cam by a spring, r², and a spring, r³, returning the arm r' and rod r into their normal position after being drawn out of the same by the cam K. When the rod r is released from the cam K as the latter rotates with the shaft S', a sudden partial rotation is thereby imparted

to the armature under the stress of the spring r³, thereby reversing or changing the polarity in the field-magnets, the current passing through the spring r⁴ to the igniter. This spring r⁴ also serves to actuate the crank-shaft S³, that has a pin, s³, that is thereby moved out of contact with the contact T, by which the current returns to the generator, and this in-

terruption produces the electric spark to ignite the charge.

Of course it will be understood that the movements of the admission, distributing, and exhaust valves and the igniter are properly timed so as to perform their functions in proper rotation.

The exhaust-valve V' opens as soon as the course of the piston has been reversed to expel the spent gases, when the admission and distributing valves V V² admit the charge, which is compressed during the completion of the backward course of the piston and ignited when said piston has reached the limit of its backward movement.

Having thus described and ascertained the nature of our said invention, what we claim, and desire to secure by Letters Patent, is—

1. In a gas-engine, a working-cylinder comprising a combustion and a piston chamber and an inclosing-easing divided by a partition to form a separate jacket for the combustion and piston chambers for the purpose of cooling the said piston-chamber and heating the said combustion-chamber, substantially as and for the purposes specified.

2. In a gas-engine, the combination, with a working-cylinder comprising a combustion and a piston chamber, and an inclosing-easing formed integral therewith, divided by a partition to form a separate jacket for the combustion and piston chambers, of a pump controlled by the piston, a connection between the pump and the jacket surrounding the piston-chamber, and a connection between the exhaust-port of the engine and the jacket surrounding the combustion-chamber, whereby a cooling agent is circulated in the jacket of the piston-chamber and a heating agent in the jacket of the combustion-chamber, substantially as and for the purposes specified.

3. In a gas-engine, the combination, with the frame thereof constructed with a hollow base to serve as a reservoir for a cooling agent, a power-cylinder comprising a combustion and a piston chamber, and an inclosing-easing formed integral therewith, divided by a partition to form a separate jacket for the combustion and piston chambers, of a pump controlled by the piston, connections between the pump, the hollow base, and the jacket surrounding the piston-chamber, and a connection between the exhaust-port of the engine and the jacket surrounding the combustion-chamber, whereby a cooling agent is circulated through the hollow base and the jacket of the piston-chamber and a heating agent in the jacket of the combustion-chamber, substantially as and for the purposes specified.

4. In a gas-engine, the combination, with the admission-valve and the governor, of means for controlling the movements of said valve and governor, consisting of the power-shaft S and driving mechanism for driving the governor, a lever having an oscillating movement imparted thereto by said power-shaft on a line with the stem of said valve, a pin or lug con-

connected with and movable on said lever, operating to impinge upon the valve-stem to move the valve off its seat when the lever is oscillated in one direction, and a connection between the lug or pin with the governor, whereby said pin is moved out of line with the valve-stem when the speed of the engine increases beyond a normal speed, substantially as and for the purpose specified.

10. 5. In a gas-engine, the combination, with the admission-valve and governor, the spindle of said governor carrying at its lower end a pin, *g*, projecting therefrom at right angles, of means for controlling the movements of said valve and governor, consisting of the power-shaft *S* and driving mechanism for driving the governor, a lever, *L*, and intermediate mechanism for oscillating said lever from said power-shaft on a line with the stem of the valve, the arm *L'* of said lever having a recess, *l*, and the pin or lug *l'*, terminating in an eye, *l*', arranged to slide in the outer end of the arm *L'* of lever *L* and project into the recess *l*, the eye of said pin engaging with the pin *g* of the governor-spindle, substantially as and for the purpose specified.

6. The combination, with the combustion-chamber of the engine, the valves *V* *V'* *V'*, the governor, the spindle of which carries at its lower end a pin, *g*, the power-shaft *S*, and mechanism for operating the governor from said shaft, of the counter-shaft *S'*, operated from the power-shaft, the cam-sleeve *D* on said shaft, the lever *L*, carrying at its outer end a sliding pin connected with the pin on the governor-spindle, and the cams *I* and *H* on shaft *S'*, for operating the valves *V'* and *V'*, respectively, said parts being arranged for operation substantially as and for the purpose specified.

40 7. The combination, with the combustion-chamber of a gas-engine and an igniter consisting of a circuit-breaker, of a dynamo con-

sisting of a series of field-magnets, an armature arranged to oscillate in the magnetic field of the magnets, a collector, a pair of brushes for taking off the currents from the collector, and electrical connections between the brushes and igniter and between the latter and the dynamo, substantially as and for the purpose specified.

8. The combination, with the piston and the combustion-chamber of a gas-engine and an igniter consisting of a circuit-breaker controlled by and timed to the movements of the piston, of a dynamo consisting of a series of field-magnets, and an armature adapted to oscillate in the magnetic field thereof, and having its poles arranged relatively to the poles of the field-magnets, so as to maintain a constant induced current in said armature, and to have the current reversed when the polarity is changed by oscillating said armature, a collector for collecting the electric currents, brushes for taking off said currents, and electrical connections between the brushes and the igniter, and means for controlling the movements of the armature from and timing the same to the movements of the piston, substantially as and for the purpose specified.

9. The combination, with the valves *V* *V'*, the stems of which project through their valve-casing, the shaft *S'*, and cams *I* *H*, of the leaf-springs *h* *h'*, interposed between the valve-stems and their respective cams, substantially as and for the purpose specified.

In testimony that we claim the foregoing we have hereunto set our hands this 1st day of March, 1886.
